UNITED STATES PATENT OFFICE.

JOHN JONES, OF PHILADELPHIA, PENNSYLVANIA.

HOT-TOP FOR INGOT-MOLDS.

1,334,036.

Specification of Letters Patent. Patented Mar. 16, 1920.

Application filed September 8, 1919. Serial No. 322,399.

To all whom it may concern:

Be it known that I, JOHN JONES, a citizen of the United States, residing at Philadelphia, in the county of Philadelphia and 5 State of Pennsylvania, have invented certain new and useful Improvements in Hot-Tops for Ingot-Molds, of which the following is a specification.

One object of my invention is to provide 10 an improved hot top which can be easily and quickly placed upon an ingot mold so as to keep a portion of the poured metal in a liquid state until the other portion of the poured metal, which forms the ingot proper, 15 has solidified.

Another object of my invention is to provide 20 a hot top of the above character which will move toward the mold during the shrinkage of an ingot poured therein and in so doing will prevent cracking and other imperfections of the ingot.

A further object is to so form my improved hot top that it can be easily made up and will be extremely durable.

25 These objects, and other advantageous ends which will be described hereinafter, I attain in the following manner, reference being had to the accompanying drawings in which—

30 Figure 1 is a sectional elevation showing my improved hot top in connection with an ingot mold and occupying a position ready for pouring,

Fig. 2 is a sectional plan view taken on the 35 line 2—2 of Fig. 1,

Fig. 3 is an outside elevation of my improved hot top looking in the direction of the arrow α of Fig. 1, a portion of the bottom of the mold being broken off,

40 Fig. 4 is a fragmentary perspective view of one of the wedges shown in Figs. 1, 2 and 3,

Fig. 5 is a fragmentary perspective view of a part of my invention,

45 Fig. 6 is a sectional elevation showing a modified form of my invention,

Fig. 7 is a fragmentary elevation, partly in section, showing the form of my invention shown in Fig. 6,

50 Fig. 8 is a perspective view of a wedge and slot connection of the form of my invention shown in Figs. 6 and 7, and

Fig. 9 is a sectional elevation showing another modification of my invention.

Referring to Figs. 1 to 5 inclusive of the drawings, 10 represents an ingot mold and 11 represents my improved hot top. The hot top as illustrated consists of three flange ring sections 12, 13 and 14 which may be secured together by any suitable means and 60 have a lining 15 of sand, clay, brick or other material which is a poor conductor of heat, said lining providing a pouring hole 16. A flange portion 17 of the lining 15 extends into the mold cavity 18 and a packing 19 is 65 stuffed or calked between the flange 17 and the inner wall of the cavity 18.

The lining 15 is preferably parted as shown at 20 at the parting between the rings 13 and 14 so that a man can easily reach 70 downwardly through the pouring hole 16 under the flange 17 to insert the calking or packing 19.

The ring 14 is provided with lugs 21 which are spaced at intervals around the 75 outer surface of the ring, as clearly shown in Fig. 2 and these lugs have tapered inner surfaces 22 to permit wedges 23 to be inserted between said surfaces 22 and the top surface 24 of the ingot 10, as clearly shown 80 in Figs. 1, 2 and 3. These wedges 23 normally hold the bottom surface 25 of the ring 14 in spaced relation above the top surface 24 of the ingot 10 and also hold the flange 17 at a normally fixed or predetermined position within the cavity 18 of the mold 10. 85

Rods 26 extend through the flanges of the rings 13 and 14 and into holes 27 in the top portion of the mold 10. These rods are 90 preferably used to keep the flange 17 centralized within the cavity 18, and the packing or calking 19 provides a seal between the cavity 18 and the outer portion of the flange 17. 95

In the use of my invention the molten metal is poured into the cavity 18 through the pour hole 16 a greater quantity of the metal being poured than is necessary to fill the cavity 18 so that a portion of the molten 100 metal fills or partially fills the pour hole 16 of the hot top 11. Any impurities or foreign material in the metal will rise to the top and this inferior portion of the metal will be located within the upper portion of 105 the molten metal adjacent the upper portion of the hot top. When the metal within the ingot cavity 18 begins to cool, it will

gradually shrink and in so doing can draw from the molten metal within the hot top, since the provision of the lining 15 keeps the metal in a molten state for a greater length of time than the metal within the mold 10, in view of the fact that the mold is usually made of metal, which is a better conductor of heat than is the lining 15. After the metal starts to shrink and turn into solid form, the wedges 23 can be knocked slowly out from under the lugs 21 and after a time these wedges can be entirely removed. This permits the shrinkage of the metal within the cavity 18 to pull or permit the hot top 11 to move toward the mold 10 so that the flange portion 17 will continue to move into the cavity 18 during the natural shrinkage of the ingot metal. By thus allowing the natural shrinkage, cracks or other imperfections of the ingot are prevented and practically a perfect ingot is produced. After the cooling, the portion of the metal within the hot top can be detached from the ingot and the ingot will be free of cracks or "pipes".

In the form of my invention shown in Figs. 6, 7 and 8 instead of using the wedges as above described, rods 28 may be employed, said rods extending through the flanges of the rings 13 and 14 of the hot top, said rods having slots 29 through which wedges 30 are driven, said wedges being positioned directly under the upper flange 31 of the ring 13. The rods 28 set within holes 32 in the ingot mold 10 and thus serve to hold the hot top in spaced relation between the bottom of the ring 14 and the top surface of the mold 10. When it is desired to permit the hot top to move toward the ingot, the wedges 30 can be driven out of the slots 29 and thus permit the flange 17 of the hot top to move into the cavity 18 of the mold 10. It will be noted that in this construction the rods 28 also serve as centering means for the flange 17 within the cavity 18 and it is unnecessary to employ additional rods, similar to the rods 26 above described, in this form of my invention.

In the form of my invention shown in Fig. 9, I have shown screw or bolt rods 33 extending through the flanges of the rings of the hot top; the lower flanges 34 having screw threaded holes through which the screw threaded portions of the rods 33 extend so that by turning the rods 33 the hot top will be permitted to move toward the mold in the same manner as described in connection with the foregoing constructions.

While I have described my invention as taking a particular form, it will be understood that the various parts of my invention may be changed without departing from the spirit thereof, and hence I do not limit myself to the precise construction set forth,

but consider that I am at liberty to make such changes and alterations as fairly come within the scope of the appended claims.

Having thus described my invention, what I claim as new and desire to secure by Letters Patent is:—

1. The combination of an ingot mold; a hot top for said mold and including a pouring hole communicating with the interior of the mold whereby the molten metal can be poured into said mold through the pouring hole and so that a portion of the molten metal can remain in the pouring hole; and means for holding said hot top to normally prevent the latter from moving toward the ingot mold, said latter means including a part movable to permit the hot top to gradually move toward the mold during the shrinking of the metal while in a molten state, said part also serving to prevent the hot top from falling unchecked toward said mold; substantially as described.

2. The combination of an ingot mold; a hot top for said mold and including a pouring hole communicating with the interior of the mold whereby the molten metal can be poured into said mold through the pouring hole and so that a portion of the molten metal can remain in the pouring hole; and means for holding said hot top to normally prevent the latter from moving toward the ingot mold, said latter means including a part movable to permit the hot top to gradually move toward the mold during the shrinking of the metal while in a molten state, said part also serving to prevent the hot top from falling unchecked toward said mold, said part being operative after the molten metal solidifies to completely release said hot top and permit it to move toward said mold during the shrinking of the ingot after the metal has solidified; substantially as described.

3. The combination of an ingot mold; a hot top for said mold and including a pouring hole communicating with the interior of the mold whereby the molten metal can be poured into said mold through the pouring hole and so that a portion of the molten metal can remain in the pouring hole; and means for holding said hot top to normally prevent the latter from moving toward the ingot mold, said latter means including a part movable to permit the hot top to gradually move toward the mold during the shrinking of the metal while in a molten state, said part also serving to prevent the hot top from falling unchecked toward said mold, said part being operative after the molten metal solidifies to completely release said hot top and permit it to move toward said mold during the shrinking of the ingot after the metal has solidified, said mold being made of a material which is a better

conductor of heat than the material of the portion of the hot top which includes the pouring hole whereby the metal within said pouring hole will remain in a liquid state 5 for a greater time than the metal which is poured into said mold; substantially as described.

In testimony whereof I have signed my name to this specification in the presence of two subscribing witnesses.

JOHN JONES.
